LIQUID FUEL ADMISSION VALVE FOR
INTERNAL COMBUSTION ENGINES

Louis Coatalen, Saint-Ouen, France

Application November 27, 1935, Serial No. 51,933
In Great Britain May 31, 1934

1 Claim. (Cl. 251—132)

In the specification of my Letters Patent No. 1,849,050 I have described and claimed a form of fuel admission valve for compression ignition engines. The valve comprises a hollow stem adapted to control the admission aperture to the engine cylinder, both ends of the stem being exposed to fuel oil pressure.

Difficulty is sometimes experienced through the leakage of fuel oil past the valve stem to the exterior of the guide piece through which the stem is inserted, and the subsequent mixing of the fuel oil which has escaped with the lubricating oil supplied to the valve operating mechanism. The object of the present invention is to enable any fuel oil which escapes past the valve stem to be collected without risk of admixture with other oil and to be returned to the fuel oil reservoir or other receptacle.

The invention consists in an improvement in or modification of the liquid fuel admission valve claimed in the specification above referred to, comprising the combination with a hollow member carrying a guide for the valve stem, of an oil chamber arranged at the upper end of the said hollow member and adapted to enclose a part of the said guide and of operating mechanism for the valve stem, and an oil discharge conduit leading from the chamber, the arrangement being such that the fuel oil which leaks past the valve stem can accumulate in the chamber, and the oil thus accumulated or some of it can escape from the chamber through the conduit.

The accompanying drawing illustrates one manner of carrying the improvement into effect.

Referring to the drawing, the valve guide *a* through which the valve stem *b* is inserted is carried in a hollow cylindrical member *c* adapted to be attached to one end of the engine cylinder (not shown). At its outer end this member *c* is extended to form a chamber *d* which surrounds the guide *a* and also encloses a part of the valve operating mechanism. The outer end of the chamber may be fitted with a cover piece *e*. The fuel oil which leaks past the valve stem can accumulate in this chamber without risk of contamination by lubricating oil, and the oil thus accumulated or some of it can be returned by a pipe *f* or other conduit to the fuel oil reservoir or other receptacle.

The valve stem is actuated by means of a pair of rods *g* situated on opposite sides of the valve guide and arranged to pass through the open end

or the cover *e*, of the chamber *d*. One pair of ends of the rods are connected to the valve stem by an annular part *h* which embraces the part *a* and which supports a part *p* extending laterally from each side of the valve stem through a transverse aperture *s* in the part *a*. By this arrangement of parts *h*, *p*, a fulcrum-like connection is provided between the valve stem *b* and its operating part *h*, so that the lifting of the valve in its guide is effected without imposing any lateral pressure on the valve. The valve is moved on to its seating by a spring *q* acting on another annular member *r* which bears on the upper side of the projection *p*. The other pair of ends of the rods extend beyond the upper end of the chamber and are connected to actuating rockers *i* or other operating means situated adjacent to the outer end of the valve guide or oil chamber.

As in my previous invention, the fuel oil is conducted by a pipe *k* to a chamber *l* in the outer end of the valve guide, and from thence it flows down the hollow interior of the valve stem to another chamber *m* at the end adjacent to the engine cylinder, the base of this chamber being formed by the nozzle *n* which is controlled by the valve.

Having thus described my invention what I claim as new and desire to secure by Letters Patent is:—

In fuel admission valves for compression ignition engines, a hollow valve stem having one end closed and an outlet adjacent the closed end, said valve stem being disposed so that both ends are exposed to fuel oil pressure and being arranged to control the admission aperture to the engine cylinder, a hollow member, a guide for the valve stem carried by said hollow member, an oil chamber arranged at the upper end of said hollow member and adapted to enclose a part of the said guide and a part of the operating mechanism for the valve stem, and an oil discharge conduit leading from the chamber, said valve stem guide having a transverse aperture, an annular member embracing the guide, a lateral projection on the valve stem passing through an aperture in the guide, the under side of which projection is supported by the annular member, means acting on said annular member for lifting the valve stem, another annular member supported on the upper side of the said projection, and a spring acting on this latter annular member for moving the valve stem to the closed position, substantially as described.

LOUIS COATALEN.
